MACHINE FOR PUTTING NUTS ON BOLTS.

No. 587,785.

Patented Aug. 10, 1897.

UNITED STATES PATENT OFFICE.

JOHN S. BROUGHTON, OF CLEVELAND, OHIO, ASSIGNOR OF ONE-HALF TO
PAUL HITCHCOCK, OF SAME PLACE.

MACHINE FOR PUTTING NUTS ON BOLTS.

SPECIFICATION forming part of Letters Patent No. 587,785, dated August 10, 1897.

Application filed March 6, 1897. Serial No. 626,179. (No model.)

To all whom it may concern:

Be it known that I, JOHN S. BROUGHTON, a citizen of the United States, residing at Cleveland, in the county of Cuyahoga and State of Ohio, have invented certain new and useful Improvements in Machines for Putting Nuts on Bolts; and I do hereby declare the following to be a full, clear, and exact description of the invention, such as will enable others skilled in the art to which it appertains to make and use the same.

The object of my invention is to provide a machine for automatically putting nuts on bolts which shall be simple and economical in construction and shall be efficient in service and not liable to get out of order. In my machine nuts carried in a suitable hopper descend a chute and are suitably held between fingers, while bolts, also descending a chute, have their heads grasped by a revolving shaft and are turned into the nuts and the nutted bolt is delivered at a desired place.

The invention consists in the combinations of parts for efficiently accomplishing this result. Those combinations are hereinafter specified, and are definitely enumerated in the claims.

The drawings show the best embodiment of my invention at present known to me.

30 Figure 1 is a side elevation, and Fig. 2 is a plan, of the machine. Fig. 3 is an end view from the left end of the preceding figures. Fig. 4 is a vertical section on the line 4-4 of Figs. 1 and 2, looking to the left of said figures.

Referring to the parts by letters, A represents the main driving-shaft of the machine, suitably supported in bearings *a a*. A belt-pulley *a'* is mounted on this shaft, and from 40 it the shaft is driven. At one end of the shaft is the bevel-gear *a²*. This bevel-gear meshes with the bevel-pinion *b* on the shaft *B*, extending horizontally at right angles to the shaft *A* and supported in bearings *b'* and *b²*. 45 A tubular hole is made in this shaft from its free end, into which projects the horizontal wrench-shaft *C*. This shaft may be moved longitudinally of the shaft *B*, but is compelled to rotate therewith by means of the spline *c*, 50 carried by one of the shafts and extending into a groove in the other. This shaft *C* has

a head *c'*, in which there is a cavity *c²* the shape of the head of the bolt to be operated upon. The drawings show a square cavity, but of course it could be hexagonal or of any required shape. The head *c'*, which forms a wrench for engaging with the bolt-head, may be removably secured to the shaft by a setscrew or other means, whereby other heads may be applied to the same shaft *C* when the machine is to operate upon bolts having differently-shaped heads.

D represents a chute for the bolts. It is composed of the plate *d*, being preferably curved, as shown, against which the heads of the bolts rest, and the two side plates *d' d'*, forming guides for the bolt-shank. The plates *d'* are held by the brackets *d''* in the position shown, whereby a space *d'''* is left between the back edge of the plates *d'* and the plate *d*, 70 into which the bolt-heads project and by which they are held in the desired position as they travel down the chute.

A disk *E*, having in its periphery a plurality of equidistant notches *e*, is secured to 75 the end of a horizontal rotatable shaft *F*, carried in suitable bearings *f* and *f'* and located, preferably, directly under the shaft *C*. This disk passes through the lower end of the bolt-chute *D*. The notches are U-shaped and of 80 a width slightly larger than the diameter of the bolt-shank, wherefore if a notch is brought under the chute by the rotation of the disk the lowest bolt in the chute drops into the notch. The disk is of such thickness relative 85 to the length of the bolt-shank that it can support a bolt and carry it around on the upper surface of its periphery as it revolves.

The perpendicular distance from the center of the shaft *F* to the center of the wrench-shaft *C* is equal to the radial distance from the center of the shaft *F* or disk *E* to the center of the bolt-shank when lying in a notch *e*. Therefore when the disk *E* is rotated it carries the bolt which it received from the chute 95 in a path which brings it directly in front of the wrench-shaft *C*. Each notch *e* is such distance from its neighbors that when one notch has come into the position in a line with the axis of the wrench-shaft *C* the preceding one is in position in the chute *D* to receive the bolt. Thus one bolt after an-

other may be automatically conveyed by the disk from the chute to the position to be operated upon by the shaft C.

The wrench-shaft C is continuously revolving, while the disk E has an intermittent movement, caused by mechanism hereinafter explained. While the disk is stationary, the wrench-shaft C is advanced longitudinally, and its head engages the head of the bolt and rotates the bolt, and thus screws it into a nut properly held to receive it. This operation is caused as follows: On the main shaft A is a cam a^3 , which engages the end of a cam-rod G, slidably held in the bearings g and pressed toward the cam by the spring g' . The other end of this cam-rod is connected by a pin-and-slot connection with the end of the shipper-lever H, pivoted on a vertical pivot h to a post h' . The other end of the shipper-lever is forked, as at h^2 , and the forks carry pins h^3 , projecting into a circumferential groove c^3 in a collar c^4 , rigidly secured to the wrench-shaft C. Therefore when the diverging surface of the cam a^4 is acting upon the cam-rod the revolving wrench-shaft C is drawn rearward, while when the cam-surface of decreasing radii comes opposite the end of the cam-rod the spring g' causes the wrench-shaft C to move forward. A considerable portion of the cam periphery is concentric, and when this part is opposite the cam-rod the spring g' advances the wrench-shaft C to its forward position, engaging with and rotating the bolt.

The nuts to be applied to the bolts are located in a hopper, (not shown,) from which the chute J leads and down which they descend by gravity. This chute is connected with its hopper in any desired manner and is capable of some movement toward or from the rest of the machine about the pivot k , provided by the bars K, which are adjustably secured by bolts d^4 to the sides of the bolt-chute D, or to other stationary support. A rock-lever L is pivoted at l to the bolt-chute near its lower end. The lever has one end adjustably connected with the nut-chute by means of the screw-rod l' and the other end with the link l^2 , which in turn is connected to the shipper-lever H at h^4 . The result of this connection between the shipper-lever and nut-chute is that as the shipper-lever, under the action of the spring g' , advances the shaft C to engage the bolt it also draws inward the nut-chute toward the bolt, and the nut held at the bottom of the nut-chute is thus fed to the bolt. After the bolt is turned into the nut the shaft C and the nut-chute are withdrawn by a reverse movement of the shipper-lever, and the nut is thus drawn out of its chute by the bolt, which remains in the notch e. A tension-spring M is provided between the nut-chute and a rigid part of the machine to steady the movement of the chute.

The lower end of the nut-chute is formed in a peculiar manner, which is as follows:

The two sides j of the chute come to an end a distance above the chute-bottom somewhat greater than the height of the nut standing on edge. The space thus left is covered by the side plates j' , which are formed as shown in Fig. 3 and have the rabbets j^2 at their upper ends, which engage with the corners of the sides and have the inwardly-projecting beveled flanges j^3 at their lower edges. The bottom plate j^4 of the chute extends laterally some distance and has at its ends the upturned flanges j^5 . Between these flanges and the plates j' are the compression-springs j^6 , held in place by knobs or pins on the respective parts, as shown. These springs cause the side plates j' to grasp the nut with sufficient force to ordinarily hold it against rotation when the bolt is being turned into the nut; but if the thread on the nut is not perfect or is a trifle small, as sometimes happens, so that the bolt turns into it so tightly that it would be difficult to remove it with the fingers, the side plates j' spread sufficiently against the action of the springs j^6 to allow the nut to turn, (the amount of spread required being reduced by the bevel-flanges j^3), and the continuance of revolution of the shaft C while in engagement with the bolt rotates both the bolt and nut. Thus in this case the bolt is delivered not with the nut turned on the usual amount, but with it only so far on as can be easily removed with the fingers. This gives as good a hold as a looser nut turned on farther. A slight bevel j^7 is formed at the base of the exit of the chute, and a spring-catch j^8 is placed at the top of the exit, so that the bottom nut may have no tendency to bound or shake out, but will be held in proper presentation to the bolt, while being easily withdrawn when the chute moves backward.

The mechanism for imparting intermittent movement to the disk E, to which I have referred, is as follows: This disk is rigidly secured, by a set-screw or other means, to one end of the shaft F. Secured to this shaft near its other end is the ratchet-wheel O, having teeth o. Beyond this ratchet-wheel, loosely mounted on a reduced end of the shaft, is the plate P. Pivoted to the inner side of this plate is the ratchet-pawl Q, adapted to engage with the teeth o. This ratchet-pawl has a lug q, extending below its pivot, and to this lug is connected a tension-spring R, the other end of which is attached to the frame or other stationary part. A link S connects the plate P with the depending arm t' of the rocker-lever T, the shaft of which oscillates in a stationary bearing t, and the other arm t'' of which engages with a crown-cam a^4 on the main shaft. The result of this connection is that as the shaft A revolves the cam a^4 rocks the lever T in the direction to move the lower end of the plate P, and hence the pawl Q, to the left of Fig. 4. This causes the pawl to pass back to the face of another ratchet-tooth and to click up into engagement with it. As

the descending face of the cam a^4 comes opposite the engaging arm of the rock-lever the spring R retracts the plate P, while keeping the pawl in engagement with the tooth, and thus 5 partially rotates the shaft F. The drawings show the positions of the parts just as one of these partial rotations is completed. Therefore with every revolution of the shaft A the shaft F is revolved such portion of a revolution 10 as corresponds to one ratchet-tooth. By this I do not mean to imply that the ratchet-teeth may not be frequent enough for the pawl to pass back over more than one tooth, and hence feed more than one. I refer in this connection 15 to the teeth by which the pawl drives the plate P, and not to any intermediate teeth it may idly click over. Now there are the same number of notches e on the disk E as ratchet-teeth which the pawl drives, and thus with every 20 revolution of the shaft A a bolt is carried by the disk E from the bolt-chute to the position to be operated upon, and the bolt which was in the latter position is carried toward the discharging position. This discharging position 25 is determined by providing a fender U, concentric with the disk for about a quadrant of its periphery beyond its operative position. This fender insures the bolts being held in place in the disk-notches until they 30 reach the quadrant below the end u of the fender, where they pass by gravity, assisted by centrifugal force, into a suitably-provided receptacle.

In order that the momentum of the shaft F 35 and attached parts shall not rotate the disk E beyond the desired point, I provide a detent W, having a nose w, suitably shaped to enter one of the notches e, and a compression-spring w', pressing the detent toward the 40 disk. This detent has a laterally-projecting arm w², with an inclined face. A correlative inclined face v' is provided on a cam-rod V, 45 slidably supported in suitable bearings v and forced toward the shaft A by a spring v². A cam a⁵, consisting of a pin projecting radially from the hub of the gear-wheel a², engages with the head of the cam-rod and, forcing the rod longitudinally, causes its face v' to engage with the arm w² and withdraw the 50 detent from engagement with the disk. This operation takes place just before the spring R begins to rotate the disk. Just before the disk has brought the next notch opposite the 55 detent the cam ceases to act on the cam-rod and the spring withdraws the latter from engagement with the detent-arm. Thereupon the spring w' forces the detent, nose first, into engagement with the periphery of the disk just in front of the approaching notch, and 60 as the notch comes opposite the detent-nose the latter springs into the notch and prevents any additional rotation of the disk from momentum, the lowest face of the cam a⁴ being such that the contact of the arm t² of the rock-lever with it stops the movement of the pawl 65 at this point.

It will be noticed that one side of the gear-wheel a² is entirely free, and hence a machine similar to that described might be placed on the other side of the shaft A (to the right in 70 Figs. 1 and 2) and its gear-pinion and cam-rods be operated by the said gear-wheel a² and the cams a³, a⁴, and a⁵. Indeed, I prefer not only to install the two machines in this manner, but to duplicate both of them on the 75 other side of the driving-pulley a', so that one main shaft and driving-pulley and two sets of cams and gear-wheels will operate four machines.

Having described my invention, I claim— 80

1. In a machine for putting nuts on bolts, in combination, a revolving shaft adapted to be reciprocated, a movable nut-chute depending in front of said shaft and having a side opening toward said shaft and in the axial line thereof, means for transferring a bolt into said axial line between said shaft and nut-chute, and means for causing said shaft and chute to simultaneously approach the interposed bolt and to simultaneously recede 90 therefrom, substantially as specified.

2. In a machine for putting nuts on bolts, in combination, a revolving shaft adapted to be reciprocated, a movable nut-chute depending in front of said shaft and having a side opening toward said shaft and in the axial line thereof, means for transferring a bolt into said axial line between said shaft and nut-chute, a pivoted lever connected with said chute and with some part which reciprocates when the shaft reciprocates, whereby said shaft and chute are compelled to move in opposite directions, and means for reciprocating said shaft, substantially as specified. 100

3. In a machine for putting nuts on bolts, 105 in combination, a revolving shaft adapted to be reciprocated, a movable nut-chute depending in front of said shaft and having a side opening toward said shaft and in the axial line thereof, means for transferring a bolt 110 into said axial line between said shaft and nut-chute, a pivoted shipper-lever adapted to reciprocate said shaft and means connecting said shipper-lever and chute, whereby said shaft and chute are compelled to move 115 in opposite directions, and means for operating said shipper-lever, substantially as specified.

4. In a machine for putting nuts on bolts, 120 in combination, a shaft, means for suitably holding a nut in the axial line thereof, means for bringing a bolt into said axial line between the shaft and nut, a continuously-revolving shaft, and a spline and groove connecting said two shafts, whereby said first-mentioned shaft 125 is continuously revolved but may be moved longitudinally, a spring tending to simultaneously force both said shaft and nut toward the bolt and a revolving cam opposing the action of said spring, substantially as specified. 130

5. In a machine for putting nuts on bolts,

- in combination, a device for loosely supporting a nut so that it may revolve, a pair of yielding spring-arms adapted to engage with opposite sides of the nut and normally prevent its rotation but capable of yielding under abnormal force and allowing rotation of the nut, a rotating wrench-shaft in axial line with the nut held between said spring-arms, mechanism for periodically moving a bolt into axial line with said wrench-shaft and nut, and means for relatively moving the wrench-shaft toward the nut-supporting device, whereby the bolt is rotated and turned into the nut if the threads on the nut and bolt properly mesh but whereby both the bolt and nut rotate idly if the nut fits too tightly, substantially as and for the purpose specified.
6. In a machine for putting nuts on bolts, in combination, a nut-chute having a bottom plate, an open front, and two yielding spring-arms at its sides, with means for supporting and rotating a bolt in line with a nut resting upon the said bottom plate, and mechanism for relatively moving the bolt and nut-chute toward each other, substantially as specified.
7. In a machine for putting nuts on bolts, in combination, a pivoted nut-chute having at its lower end means for supporting the lowest nut therein, said chute having an opening in its front side for the withdrawal of said lowest nut, a longitudinally-movable rotating wrench-shaft, and means for simultaneously moving said chute and wrench-shaft toward and from each other, with a bolt-chute, a disk having notches in its edge into which the bolts fall, and means for intermittently turning said disk to bring the bolt therein into line

with the lowest nut in the nut-chute, substantially as specified.

8. In a machine for putting nuts on bolts, in combination, a swinging nut-chute having in its lower end means for supporting and preventing the rotation of the lowest nut in the chute, a longitudinally-movable rotating wrench-shaft, and means for holding a bolt in line with said wrench-shaft and lowest nut, with a fork-lever for moving the wrench-shaft, a spring actuating said fork-lever in the direction which moves the wrench-shaft toward the nut-chute, and a cam for moving said lever in the reverse direction, substantially as specified.

9. In a machine for putting nuts on bolts, in combination, a swinging nut-chute having in its lower end means for supporting and preventing the rotation of the lowest nut in the chute, a longitudinally-movable rotating wrench-shaft, and means for holding a bolt in line with said wrench-shaft and lowest nut, with a fork-lever for moving the wrench-shaft, a spring actuating said fork-lever in the direction which moves the wrench-shaft toward the nut-chute, a cam for moving said lever in the reverse direction, mechanism connecting the nut-chute and fork-lever, whereby the nut-chute is moved simultaneously with bolt in the reverse direction to the wrench-shaft, substantially as specified.

In testimony whereof I affix my signature in presence of two witnesses.

JOHN S. BROUGHTON.
